UNITED STATES PATENT OFFICE

108,927

DESIGN FOR A LUBRICANT - RECEIVING FITTING

Frank S. Barks, St. Louis, Mo., assignor to Lincoln Engineering Company, St. Louis, Mo., a corporation of Missouri

Application January 19, 1938, Serial No. 74,397

Term of patent 14 years

To all whom it may concern:

Be it known that I, Frank S. Barks, a citizen of the United States, and a resident of St. Louis, Missouri, have invented a new, original, and ornamental Design for a Lubricant-Receiving Fitting, of which the following is a specification, reference being had to the accompanying drawing, forming part thereof, in which

Fig. 1 is a plan view of a lubricant-receiving fitting, showing my new design;

Fig. 2 is a side elevation thereof.

I claim:

The ornamental design for a lubricant-receiving fitting, as shown.

FRANK S. BARKS.
